UNITED STATES PATENT OFFICE.

CHARLES J. GADD, OF LEBANON, PENNSYLVANIA.

FEEDING PULVERIZED FUEL.

Specification of Letters Patent. Patented Apr. 11, 1916.

1,179,087.

Application filed March 12, 1914. Serial No. 824,091.

To all whom it may concern:

Be it known that I, CHARLES J. GADD, a citizen of the United States, and a resident of Lebanon, in the county of Lebanon and 5 State of Pennsylvania, have invented certain new and useful Improvements in Feeding Pulverized Fuel, of which the following is a specification.

This invention relates to an apparatus for 10 feeding pulverized fuel in regulated quantities from a hopper to a pressure blast pipe which carries it to a furnace, kiln or other place where it can be burned.

In the gravity feeding of pulverized fuel 15 from a hopper, such material frequently forms a bridge or "scaffold" above the mouth of the hopper, and when such a scaffold breaks a large mass of the material sometimes flows into the feeding apparatus 20 in excess of the amount required in regular feeding. It has been found that the material, owing to its weight and slippery character will even force itself around through the spiral conduit of a spiral 25 veyer in advance of the movement of the spiral wing thereof and cause an irregular feeding. In open hearth furnaces especially this is not only objectionable but a fatal defect.

30 The principal object of the invention is to avoid the irregular in-rush referred to and to secure a steady feed of the material along the top channel of the casing from the top opening thereof to a point in the descending leg thereof above the blast pipe, whence it 35 passes in a falling stream across the blast pipe openings, and a take-up and return of that portion of the material which passes by said openings.

40 In the accompanying drawings forming part of this specification and in which similar letters of reference indicate similar parts throughout the several views:—Figure 1, is a plan view of my pulverized fuel feed-

45 ing apparatus: Fig. 2, a section of Fig. 1 on line A—A: Fig. 3, a section of Fig. 2 on line B—B: Fig. 4, a section of Fig. 2 on line C—C: Fig. 5, a side elevation of the device showing a means for driving the 50 feeding belt electrically: Fig. 6, a front elevation showing two feeding belts placed side by side and staggered: Fig. 7, a side elevation of Fig. 6.

55 The same reference numbers indicate corresponding parts in the different figures.

In the embodiment of the invention illustrated in the drawings, the apparatus comprises a chamber or case 1 consisting of an endless closed channel, constructed approximately in triangular form. The base of the 60 triangle is at the top thereof and the apex at the bottom thereof. The endless channel is horizontal along the top of the case, a descending leg is connected with one end thereof and an ascending leg connects the lower 65 end of the descending leg with the top portion of the channel. The top is provided with an opening 2 which is surmounted by hopper 3, which serves to feed the material by gravity into the horizontal channel at 70 the top of the casing. The descending leg is broadened laterally.

Within the case 1 are three sprocket 75 wheels 4—5—6 the journals of which are carried in castings 7—8 which are secured to the sides of the case 1 by bolts 9 and passing around these wheels is a belt 12 carrying flights or scrapers 13.

10—11 is a pressure blast pipe one end of 80 which, as 10, enters one side of casing 1 and the other, as 11, enters the other side of the casing. As usual one end of the pressure blast pipe is connected with a blower and the other end is connected with a furnace in 85 which the fuel is burned. Both the blower and furnace being well known and forming no part of my invention, are not illustrated.

The pulverized fuel drops from the hopper 3 through the opening 2 at the top 90 of the case into the upper channel thereof and the flights of the endless chain conveyer carry it along said top channel past said opening to a point above the blast pipe in the descending leg of the case. The flights 95 13 practically fill the space between the opening 2 and the delivery point of the conveyer and serve as stops to prevent any sudden influx of material from the hopper to the feeder.

100 The pulverized fuel falling from the belt 12 at the periphery of pulley 4 drops upon a guide plate 20, which may be part of the casting of case 1, which directs it past the open ends of the pipes 10—11 and a great 105 part of it is carried by the blast passing through these pipes into the one that leads to the furnace, the one 11 for instance. That portion of the fuel that is not drawn into pipe 11 falls to the bottom of case 2 where 110 it is engaged by the flights 13 of the belt 12

and is carried between these flights and the side of the case 1 up under the hopper 3 and is presently, together with the fuel dislodged from the hopper by the flights 13 as 5 they pass beneath it, dropped down past the blast pipe when more or less of it is carried to the furnace.

It will be observed from Fig. 2 that the center of the sprocket 6 at the lower end of 10 the case 1 is placed to the right of the center line of the case, and from Fig. 5 that the journals of this sprocket are carried off center by the castings 7. By taking out the stud bolts 9 which secure the castings 7 to 15 case 1 and by moving these castings around so as to bring the bolt holes in them into register with other bolt holes 14 in the case 1 the journals of sprocket 6 are moved toward or away from the bottom of case 1 as may 20 be necessary to adjust the tension of belt 12.

At its bottom the case 1 carries a plate 15, held in place by bolts 16, which can be removed to clean out the case when necessary.

The conveyer in the case 1 may consist of 25 a single belt 12 as shown in Figs. 1, 2, 3, 4 and 5, or it may be made of two or more belts placed side by side as shown in Figs. 6 and 7. In this case the belts are arranged with their flights 13 staggered or alternately 30 arranged so that the fuel will be delivered by them alternately and with a more regular flow than is possible by a single belt.

The belt 12 is constructed of a number of links 21 which are pivotally connected as is 35 usual in link belt constructions. It will be observed from Fig. 2 that the belt 12 is driven counter-clock-wise, as indicated by the arrow, and that when it passes over the pulley 4 that the change in direction of the 40 links 21 will cause the flights 13 to separate, at this time the ends of the hooks 22 on one end of the links 21 are rotated around the pins 23 on the adjacent end of the adjoining link and the fuel carried between the flights 45 is thus disturbed and facilitated in falling from the belt as this latter passes down around the sprocket 4.

The outer and inner walls 24—25 of the case 1, together with its side walls, may be, 50 and preferably are, formed in a single casting to which is bolted the castings or plates 7—8 carrying the journals of the sprocket wheels carrying the belt. The inner wall of the case is provided with recesses at the 55 angles for the sprocket wheels.

The belt 12 and its sprockets may be driven in any suitable manner. In the drawings, more particularly in Fig. 5 the shaft of sprocket 4 carries a gear wheel 17 which is 60 driven by a gear wheel 18 carried upon the armature shaft of an electric motor 19. Any other means for the purpose may be employed, but the electric motor drive is of advantage as it makes a complete, self-contained and compact unit of each feeder. 65

Having thus described my invention I claim as new and desire to secure by Letters Patent:

1. An apparatus for feeding pulverized fuel in regulated quantities comprising a 70 chamber consisting of an endless closed channel including a descending leg and an ascending leg, an endless chain conveyer traversing said endless channel, a blast pipe connected with opposite openings of opposite walls of said descending leg above the lower end thereof and below the upper end thereof and at one side of said endless conveyer, a hopper surmounting said chamber and opening into the top thereof, the 75 flights of said endless chain conveyer serving to practically close said channel between the hopper opening thereof and said descending leg, said endless chain conveyer passing above and below said blast pipe 80 openings and being operative to deliver fuel from said hopper into said descending leg above said blast pipe and to pick up and return the fuel which falls below said blast pipe, and means for driving said endless 85 chain conveyer.

2. An apparatus for feeding pulverized fuel in regulated quantities comprising a 90 chamber consisting of an endless closed channel including a descending leg of enlarged area and an ascending leg, an endless chain conveyer traversing said endless channel, a blast pipe connected with opposite 95 openings of opposite walls of said descending leg above the lower end thereof and below the upper end thereof and at one side of said endless conveyer, a hopper surmounting said chamber and opening into the top thereof, the flights of said endless chain conveyer serving to practically close said channel between the hopper opening thereof and said descending leg, said endless chain conveyer passing above and below said blast pipe 100 openings and being operative to deliver fuel from said hopper into said descending leg above said blast pipe and to pick up and return the fuel which falls below said blast pipe, an inclined guide plate above said 105 openings, and means for driving said endless chain conveyer.

3. An apparatus for feeding pulverized fuel in regulated quantities comprising a 110 chamber consisting of an endless closed triangular channel including a descending leg of enlarged area and an ascending leg, an 115 endless chain conveyer traversing said endless channel, a blast pipe connected with opposite 120 openings of opposite walls of said descending leg above the lower end thereof and below the upper end thereof and at one side of said endless conveyer which passes through said leg on an inclined path, a hopper surmounting said chamber and opening into the top thereof, the flights of said endless chain conveyer 125 130

serving to practically close said channel between the hopper opening thereof and said descending leg, said endless chain conveyer passing above and below said blast pipe openings and being operative to deliver fuel from said hopper into said descending leg above said blast pipe and to pick up and re-

turn the fuel which falls below said blast pipe, and means for driving said endless chain conveyer.
